(57) **CLAIM**

The ornamental design for a display screen or portion thereof with graphical user interface for display of content approval, as shown and described.

DESCRIPTION

The sole FIGURE is a front view of a display screen or portion thereof with graphical user interface for display of content approval showing our new design.

The dashed lines shown as part of an icon are claimed elements of the design. The dashed horizontal rule is not claimed. The broken line showing of the display screen or portion thereof and the remainder of the graphical user interface forms no part of the claimed design.
